UNITED STATES PATENT OFFICE.

VALENTIN NYEZNICK AND STANLEY JANKOWSKI, OF AKRON, OHIO.

WINDOW SHADE.

Application filed April 24, 1928. Serial No. 272,392.

This invention relates generally to windows, and has more particular reference to a novel shade therefor.

The invention has for an object the provision of a device of the class mentioned which is of simple durable construction, desirable and efficient in action, and which can be manufactured and sold at a reasonable cost.

10 The device consists of a spring actuated roller with a shade wound thereon. The roller is mounted within a window frame, and the free end of the shade is manually movable to various positions. The edges of 15 the shade are guided between strips for holding purposes, arranged on the window frame.

For further comprehension of the invention, and of the objects and advantages 20 thereof, reference will be had to the following description and accompanying drawings, and to the appended claim in which the various novel features of the invention are more particularly set forth.

25 In the accompanying drawing, forming a material part of this disclosure:

Fig. 1 is a front elevational view of a window as seen from the inside of a room, and provided with the shade device.

30 Fig. 2 is a fragmentary view similar to Fig. 1 but showing the shade slightly raised.

Fig. 3 is a fragmentary horizontal sectional view, taken on the line 3—3 of Fig. 1.

Fig. 4 is a similar view, taken on the line 35 4—4 of Fig. 1.

Fig. 5 is an enlarged detail view of the shade strips shown in Fig. 4.

Fig. 6 is a fragmentary perspective detail view of one of the said shade strips.

40 Fig. 7 is a horizontal sectional view taken on the line 7—7 of Fig. 6.

Fig. 8 is a similar view of the other shade strip.

Fig. 9 is a fragmentary vertical sectional view, taken on the line 9—9 of Fig. 1.

Fig. 10 is a view similar to Fig. 5 but illustrating a modification thereof.

Fig. 11 is a fragmentary perspective detail view of one of the shade strips shown in 50 Fig. 10.

Fig. 12 is a similar view of the other shade strip.

The reference numeral 10 indicates generally an inner window sash and 11 an outer 55 window sash, these sashes being provided with glass 12. The sashes 10 and 11 are

slidably mounted in a window frame 13 provided with the sash guide strips 14. A shade 16 has a bracket 15 secured near its free edge for manual grasping thereof in raising and 60 lowering the same.

The shade member 16 is wound on a spring operated roller 17 arranged within the frame 13 and adapted to normally wind the screen upon itself. As indicated in Fig. 65 1 both the top and the bottom of the window frame may be provided with the roller and shade members.

The edges of the shade 16 are provided at their free ends with pointed gripping 70 members 18 engageable in apertures 19 formed in shade strips 20 provided with integral right angle flanges 21. Small facial recesses 22 communicate with each of the apertures 19. Cover strips 23 are hingedly 75 connected to the free edges of the strips 20, and frictionally maintain positions parallel with the flanges 21 or positions aligned with the strips 20. The gripping members 18 are preferably attached on the edges of the 80 shade 16 at points in line with a springy strip 16^a built into the shade and extending completely across the shade, bending of the springy strip being depended upon for permitting the engaging and disengaging of 85 the members 18 in the apertures 19 and recesses 22.

In operation the cover strips 23 are manually moved to positions aligned with the strips 20 as indicated by dot dash lines 24 90 in Figs. 5 and 9. Then the shade 16 may be manually moved inwards with respect to the inner side of the windows to a position as indicated by the dot dash lines 25. It may next be drawn upwards against the 95 action of roller 17 or allowed to move downwards, reference being had to the lower roller 17. The operation of the upper roller 17 is similar. Next the free end of the shade 16 is moved outwards so that the gripping 100 members 18 pass along recesses 22 and engage in apertures 19. The cover strips 23 are then moved to positions parallel with the flanges 21. Obviously the extended positions of the shades depend upon which of the 105 apertures 19 the gripping members engage.

In the modified form of the device illustrated in Figs. 10, 11 and 12 the edges of the shade 16 are guided between shade guide plates 26 and 27. The plate 26 has an integral flange 28 secured to the window frame 13 by the screws 30. A plurality of studs

31 project from the plate 26 thru slots 32 in a flange 33 integral with the plate 27. Nuts 34 are engaged upon the studs 31 for slidably holding the flanges 28 and 33 together.

5 Springs 35 project from the flange 28 thru slots 36 in the same flange 33, and these springs act against the plate 26 for urging it towards the plate 27. Thus the plates 10 26 and 27 engage the edges of the shade 16 for holding the shade in any extended or retracted position to which it is manually 15 placed and for preventing insects from walking around the edges of the shade. Obviously the plates may engage shades of different thicknesses.

While we have shown and described the preferred embodiment of our invention, it is to be understood that we do not limit 20 ourselves to the precise construction herein disclosed and the right is reserved to all changes and modifications coming within the scope of the invention as defined in the appended claim.

Having thus described our invention what 25 we claim as new and desire to secure by United States Letters Patent is:

In a device of the class described, a shade strip for attachment on the side of a window frame, and provided with an integral right 30 angle flange, and formed with apertures, communicating with facial recesses, and a cover strip hingedly connected on the free edge of the said shade strip, and arranged 35 for frictionally maintaining a position parallel with the flange or aligned with the shade strip for permitting the engagement of the edge of a shade between the said right angle flange and the cover strip so that a gripping member attached on the edge of 40 the shade may engage in certain of the said apertures for holding the shade in an extended position.

In testimony whereof we have affixed our signatures.

VALENTIN NYEZNICK.
STANLEY JANKOWSKI.
